UNITED STATES PATENT OFFICE.

ADELARD B. SIMONEAU, OF WATERVILLE, MAINE.

PICKER-ACTION FOR LOOMS.

1,373,028.

Specification of Letters Patent. Patented Mar. 29, 1921.

Application filed April 5, 1920. Serial No. 371,422.

To all whom it may concern:

Be it known that I, ADELARD B. SIMONEAU, a citizen of the United States, residing at Waterville, in the county of Kennebec and 5 State of Maine, have invented certain new and useful Improvements in Picker-Actions for Looms, of which the following is a specification.

This invention relates to picker actions 10 for looms and has for an object to provide means for actuating the picker from the oscillation of the lay imparting to the pickers the much-to-be-desired quickness and decisiveness of impulse for actuating the 15 shuttle.

The further object of the invention is to provide a cam rotated with a step-by-step movement from the lay, such cam actuating a system of levers which impart the required motion to the pickers alternately at 20 opposite ends of the lay.

With these and other objects in view the device comprises certain novel elements, units and combinations as will be herein- 25 after more fully described and claimed.

In the drawings,

Figure 1 is a view of a conventional loom shown in rear elevation showing the picker actuating mechanism.

30 Fig. 2 is a top plan view of so much of the loom as may be necessary to show the action, the superstructure being broken away.

Fig. 3 is a vertical sectional view taken 35 on line 3—3 of Figs. 1 and 2 showing the cam and the means of actuating the same from the oscillation of the lay.

Fig. 4 is a view on the same plane as Fig. 3 with the lay advanced to begin the turning 40 of the cam.

Fig. 5 is a view on the same plane as Figs. 3 and 4 with the lay advanced to its limit and the cam completely turned a quarter of a revolution.

45 Like characters of reference indicate corresponding parts throughout the several views.

The improved picker action which forms the subject matter of this application is 50 adapted to operate in conjunction with looms of various types, as for instance the loom disclosed in co-pending application Serial Number 352,438 filed January 19, 1920, but it is to be understood that it is 55 not in any way limited to co-action with that identical loom.

A conventional loom frame 10 supports a lay of substantially the usual and ordinary type pivoted at 11 and carrying a reed 12 a shuttle race and shuttle boxes 13. 60 Operating also with the lay are pickers 14 and 15 in substantially the usual and ordinary manner, so far as their traveling with the lay is concerned or their relation to the shuttle race.

To the pickers 14 and 15 cables 16 and 17 are secured, passing over pulleys 18 and 19 respectively, and connected with levers 20 and 21.

At the rear of the lay a cam member 70 22 is journaled being preferably square through the major portion of its length and provided with an arm 23 held by the spring 24 upon the squared portion of the cam member 22 whereby the said member is held 75 against rotation until rotated by mechanism provided for that purpose. The mechanism for rotating the member 22 comprises a detent 25 pivoted to the lay at 26, and engaging ratchet teeth 27 formed in the member 22. The detent 25 is controlled by the spring 28. The detent 25 is provided with spaced teeth or shoulders 29 and 30, properly proportioned and spaced to engage the ratchet teeth 27 when the cam member 22 80 rotates.

The position of attaching the detent 25 to the lay is such that the swing of the lay, through its complete cycle, moves the detent 25 a sufficient distance to rotate the 90 member 22 one quarter of a revolution. As shown at Fig. 3 the lay is in its extreme forward position. Upon starting to the rear the tooth 29 engages one of the teeth and moves the member 22 upon its journal as 95 indicated at Fig. 4 until the tooth 30 engages the next succeeding tooth 27 whereupon the completion of the movement of the lay completes the one quarter revolution of the member 22, as indicated at Fig. 5. 100

The rotation of the member 22 is translated into picker actuating motion by employing cam sections 31 and 32 engaging against strikers 33 and 34, respectively. The strikers 33 and 34 extend upwardly and bear 105 upon the levers 20 and 21. As the member 22 is rotated by the oscillation of the lay the cams 31 and 32 alternately depress the strikers 33 and 34. The depression of these strikers actuating the levers 20 and 21, respectively, act through the cables 16 and 17 to actuate the pickers 14 and 15. Springs 110

35 and 36 are employed to return the pickers 14 and 15 to the outer limit of their movements also serving to raise the levers 20 and 21 and the strikers 33 and 34 when 5 the latter are released by the further rotation of the cam member 22.

It will be apparent, therefore, that at each oscillation of the lay the member 22 is given one quarter of a revolution, changing the 10 relative positions of the cams 31 and 32, and, likewise, the relative positions of the strikers 33 and 34. The change of such positions of the strikers actuates the pickers to impart to the shuttle the required 15 movement in the usual well-known manner.

Having thus fully described my said invention what I claim as new and desire to secure by Letters Patent is:

1. The combination with a loom embody- 20 ing an oscillating lay and pickers carried thereby, a cam member journaled adjacent the lay, strikers associated with the cam member adapted to be alternately depressed by the cams, means transmitting motion 25 from the strikers to the pickers comprising levers on the lay adapted to be depressed by the strikers and means carried by the lay for rotating the cam member with a step-by-step movement.

2. The combination with a loom embody-

ing an oscillating lay and pickers carried thereby, of a cam member journaled adjacent the lay, means to retard rotative movement of the cam member, strikers positioned to be alternately depressed by the cam 35 member, levers connected with the pickers and positioned to be struck by the strikers and means carried by the lay to rotate the cam member with a step-by-step movement.

3. The combination with a loom embody- 40 ing an oscillating lay and pickers carried thereby, pivoted levers connected with the pickers, strikers positioned to alternately strike and depress the levers, a member journaled adjacent the lay, cams carried by 45 the journaled member operating upon the strikers and pawl and ratchet actions between the lay and journaled member whereby oscillation of the lay is translated into step-by-step rotative movement of the 50 journaled member.

In witness whereof I have hereunto set my hand and seal at Waterville, Maine, this first day of April, A. D. nineteen hundred and twenty.

ADELARD B. SIMONEAU. [L. S.]
